ARTICLE OF REPOSE FOR SUPPORTING THE BODY OF A PERSON

Johannes Luckhardt, deceased, Berlin-Dahlem, Germany, by Wassili Luckhardt, administrator, Berlin-Dahlem, Germany, assignor to Anton Lorenz, Boynton Beach, Fla.

Filed Apr. 6, 1955, Ser. No. 499,724

4 Claims. (Cl. 155—106)

This invention relates to articles of furniture and more particularly to articles of repose for supporting the body of a person wherein a back-rest, seat and leg-rest are movable in a predetermined relationship relative to a support.

An object of the invention is to provide an article of repose of above described type with an advantageous mechanism for controlling the movements of the leg-rest in dependence on movements of the back-rest.

Another object of the invention is to improve on the construction of articles of repose as now customarily made.

Other objects and structural details of the invention will be apparent from the following description when read in conjunction with the accompanying drawings forming part of this specification, wherein:

Fig. 1 is a side elevational view of an adjustable reclining chair according to the invention, a portion of a side wall being broken away,

Fig. 2 is a similar side elevational view of the chair shown in Fig. 1, wherein however the movable members of the chair are in the extreme reclined position,

Fig. 3 is a side elevational view of another embodiment of an armchair according to the invention, a portion of a side wall being broken away,

Fig. 4 is a similar side elevational view of the armchair shown in Fig. 3, wherein however the movable members of the chair are in the extreme reclined position,

Fig. 5 is a side elevational view of a further embodiment of an armchair according to the invention, a portion of a side wall being broken away, and

Fig. 6 is a similar side elevational view of the chair shown in Fig. 5, wherein however the movable members of the chair are in the extreme reclined position.

Referring now to Figs. 1 and 2, 10 generally indicates a support having suitably connected side walls 12 and 14 and a rear wall 16.

A back-rest generally indicated by 18 is swingably mounted on the support 10 at 20. An extension 22 rigid with the back-rest 18 projects downwardly beyond the pivot 20.

A seat 24 is swingably mounted on the support 10 at 20 in coaxial alignment with the pivotal connection between the back-rest 18 and the support 10.

On each side of the chair a first arm 26 is swingably mounted on the support 10 at 28. A second arm 30 arranged to the rear of the first arm 26 is swingably mounted on the support 10 at 32, at a point spaced from the pivotal connection 28 between the first arm 26 and the support 10.

The rear end of a link 34 is pivoted to an intermediate point of the first arm 26 at 36. The front end of said link 34 is pivoted at 38 to the upper portion of a leg-rest 40. The lower portion of said leg-rest 40 is pivoted at 42 to the front end of a curved link 44. An intermediate point of said curved link 44 is pivoted at 46 to the lower end of the first arm 26. The rear end of the curved link 44 is pivoted at 48 to the lower end of the second arm 30.

2

A first connecting link 50 is pivoted to the first arm 26 at 52 and to the seats 24 at 54. Thus movements of the seat 24 are controlled by said first connecting link 50 in dependence on movements of the first arm 26. If desired however, said connecting link 50 may be replaced by different means for controlling movements of the seat 24 in dependence on movements of the first arm 26.

The rear end of a second connecting link 56 is pivoted to the downward extension 22 of the back-rest 18 at 58.

10 The front end of said second connecting link 56 is pivoted to the first arm 26 at 36 in coaxial alignment with the pivotal connection between the first arm 26 and the link 34. If desired, however, the pivotal connection between the second connecting link 56 and the first arm 26 may be spaced from the pivotal connection between the first arm 26 and the link 34. Thus, the second connecting link 56 controls the movements of the first arm 26 and thereby the movements of the seat 24 and of the leg-rest 40 in dependence on movements of the back-rest 18.

15 The relative movements of the back-rest 18, seat 24 and leg-rest 40 are determined by the constrained linkage described above. The sitting position is shown in Fig. 1 and the extreme reclined position is shown in Fig. 2.

20 According to the embodiment shown in Figs. 3 and 4, the arrangement of the back-rest 118, the seat 124, the leg-rest 140 and the links or arms 130, 144, 126, 150 and 134 relative to each other and relative to the support 110 respectively is the same as in the embodiment

25 described above in connection with Figs. 1 and 2. However according to Figs. 3 and 4 the second connecting link 156 is pivoted at one of its ends to the downward extension 122 of the back-rest 118 and at its other end to the second arm 130 at 160.

30 Upon a rocking movement of the back-rest 118 from the upright position shown in Fig. 3 into the reclined position shown in Fig. 4, the constrained linkage 156, 130, 144, 126, 150 and 134 causes a movement of the leg-rest 140 from the position shown in Fig. 3 into the position shown in Fig. 4.

35 According to the embodiment shown in Figs. 5 and 6, the back-rest 218 and seat 224 are rigid with each other so as to form a unit generally indicated by 262. Said unit 262 is swingably mounted on the support 210 at 264.

40 Again a first arm 226 and a second arm 230 are swingably mounted on the support 210 at spaced points 228 and 232 respectively. Furthermore, again the leg-rest 240 is pivoted at 238 to one end of a link 234, the other end of which is pivoted to the first arm 226 at 236. The lower portion of the leg-rest 240 is pivoted at 242 to the front end of the curved link 244, which is pivotally connected with the first arm 226 and the second arm 230 at the spaced points 246 and 248.

45 55 The control of the movements of the linkage 230, 244, 226, 234, 240 in dependence on the rocking movements of the unit 262 however is obtained by different means. According to Fig. 5 the lower end of a downward extension 266 of the unit 262 is pivoted at 268 to

60 one end of a link 270, the other end of which is pivoted at 272 to a third arm 274 swingably mounted on the support 210 at 276. The lower end of said third arm 274 is pivoted at 278 to one end of a link 280, the other end of which is pivoted to the first arm 226 at 282.

65 70 A rocking movement of the unit 262 around its pivot 264 from the sitting position shown in Fig. 5 into the extreme reclined position shown in Fig. 6 will cause an upward and forward propelling of the leg-rest 240 from the position shown in Fig. 5 into the position shown in Fig. 6 by means of the link mechanism described above.

The preferred embodiments of the invention have been described, but it is understood that this disclosure

is for the purpose of illustration and that various changes in shape, proportion of parts, as well as the substitution of equivalent elements for those herein shown and described, may be made without departing from the spirit and scope of the invention as set forth in the appended claims.

The sitting and extreme reclined positions may be limited by suitable stops. Furthermore, locking means may be provided for holding the movable members in any desired position.

What is claimed is:

1. An adjustable reclining chair comprising a support, body-supporting means including a seat and back-rest pivotally mounted on said support and movable between an upright sitting position and a rearwardly tilted reclining position, a leg-rest, and a leg-rest control arrangement operatively connected between said support and said leg-rest and actuated by said body-supporting means for movement of the leg-rest relative to said seat in response to movement of said body-supporting unit, said control arrangement including a first arm pivotally mounted on the support and depending therefrom, a second arm pivotally mounted on the support at a point to the rear of said first arm and depending from its pivotal mount, a first link pivotally connected to an intermediate point on said first arm and to said leg-rest, a second link pivotally connected to the lower end of said second arm and pivotally connected to said leg-rest at a point spaced from the connection of said first link to said leg-rest, the lower end of said first arm being pivotally connected to an intermediate point on said second link, said body-supporting means having a depending extension projecting below the pivotal mount of said body-supporting means on said support for forward and upward movement when said body-supporting means is moved to its reclined position, and an actuating link connecting said depending extension to one of said arms whereby to actuate said leg-rest linkage.

2. An adjustable reclining chair comprising a support, body-supporting means including a seat and back-rest pivotally mounted on said support and movable between an upright sitting position and a rearwardly tilted reclining position, a leg-rest, and a leg-rest control arrangement operatively connected between said support and said leg-rest and actuated by said body-supporting means for movement of the leg-rest relative to said seat in response to movement of said body-supporting unit, said control arrangement including a first arm pivotally mounted on the support and depending therefrom, a second arm pivotally mounted on the support at a point to the rear of said first arm and depending from its pivotal mount, a first link pivotally connected to an intermediate point on said first arm and to said leg-rest, a second link pivotally connected to the lower end of said second arm and pivotally connected to said leg-rest at a point spaced from the connection of said first link to said leg-rest, the lower end of said first arm being pivotally connected to an intermediate point on said second link, said body-supporting means having a depending extension projecting below the pivotal mount of said body-supporting means on said support for forward and upward movement when said body-supporting means is moved to its reclined position, and an actuating link connecting said depending extension to one of said arms whereby to actuate said leg-rest linkage, said second arm being inclined rearwardly and downwardly relative to said first arm for increasing the effective length of

said second arm and second link when said leg-rest is actuated.

3. An adjustable reclining chair comprising a support, body-supporting means including a seat and back-rest rigid with each other pivotally mounted on said support and movable between an upright sitting position and a rearwardly tilted reclining position, a leg-rest, and a leg-rest control arrangement operatively connected between said support and said leg-rest and actuated by said body-supporting means for movement of the leg-rest relative to said seat in response to movement of said body-supporting unit, said control arrangement including a first arm pivotally mounted on the support and depending therefrom, a second arm pivotally mounted on the support at a point to the rear of said first arm and depending from its pivotal mount, a first link pivotally connected to an intermediate point on said first arm and to said leg-rest, a second link pivotally connected to the lower end of said second arm and pivotally connected to said leg-rest at a point spaced from the connection of said first link to said leg-rest, the lower end of said first arm being pivotally connected to an intermediate point on said second link, said body-supporting means having a depending extension projecting below the pivotal mount of said body-supporting means on said support for forward and upward movement when said body-supporting means is moved to its reclined position, and an actuating link connecting said depending extension to one of said arms whereby to actuate said leg-rest linkage.

4. An adjustable reclining chair comprising a support, body-supporting means including a separate seat and back-rest pivotally mounted on said support for independent movement between an upright sitting position and a rearwardly tilted reclining position, a leg-rest, and a leg-rest control arrangement operatively connected between said support and said leg-rest and actuated by said body-supporting means for movement of the leg-rest relative to said seat in response to movement of said body-supporting unit, said control arrangement including a first arm pivotally mounted on the support and depending therefrom, a second arm pivotally mounted on the support at a point to the rear of said first arm and depending from its pivotal mount, a first link pivotally connected to an intermediate point on said first arm and to said leg-rest, a second link pivotally connected to the lower end of said second arm and pivotally connected to said leg-rest at a point spaced from the connection of said first link to said leg-rest, the lower end of said first arm being pivotally connected to an intermediate point on said second link, said back-rest having a depending extension projecting below the pivotal mount of said back-rest on said support for forward and upward movement when said back-rest is moved to its reclined position, an actuating link connecting said depending extension to one of said arms whereby to actuate said leg-rest linkage, and a seat control link pivotally connected to said first arm and to the forward end of said seat for tilting the seat in response to movement of the back-rest to its reclined position.
